(57) **CLAIM**

The ornamental design for a lanyard theft deterrent apparatus, as shown and described.

DESCRIPTION

FIG. 1 is a top plan view of a lanyard theft deterrent apparatus; FIG. 2 is a bottom plan view of the apparatus;

FIG. 3 is a top plan view of a theft deterrent apparatus with the retraction handle raised;

FIG. 4 is a left hand top perspective view of the apparatus;

FIG. 5 is a left side elevational view of the apparatus;

FIG. 6 is a front end right side perspective view of the apparatus;

FIG. 7 is a front end right side bottom perspective view of the apparatus; and,

FIG. 8 is a rear end right side bottom perspective view of the apparatus, wherein the left side view is a mirror image.
